UNITED STATES PATENT OFFICE.

OLIVER COLBORNE, OF CHICAGO, ILLINOIS.

RIMMING-MACHINE.

1,071,881.

Specification of Letters Patent.

Patented Sept. 2, 1913.

Application filed September 12, 1910, Serial No. 581,550. Renewed May 6, 1912. Serial No. 695,570.

To all whom it may concern:

Be it known that I, OLIVER COLBORNE, a citizen of the United States of America, and a resident of Chicago, county of Cook, State 5 of Illinois, have invented certain new and useful Improvements in Rimming-Machines, of which the following is a specification.

The main objects of this invention are to provide improved mechanism for shaping 10 the edges of pie crust so as to form an up-standing rim thereon capable of retaining soft material when the crust is filled to a depth greater than that of the tins; and to provide improved means for preventing the 15 pie crust from adhering to the form after the rim is completed.

A specific construction embodying this invention is illustrated in the accompanying drawing, which is an enlarged sectional 20 detail of those parts of a pie crust rimming machine to which the present invention relates.

In the construction shown in the drawings, the pie tin 1 is carried by a support 25 2 mounted at the upper end of an upright 3, which is arranged to move vertically in the supporting frame of the machine so as to carry the pie tin and its contents into and out of engagement with the rim forming 30 mechanism which is mounted above the support 2. The up and down movement of the upright 3 is accomplished by means of a strap 4, which is secured to the lower end 5 of the upright 3, and passes over a pulley 35 6 to operating mechanism, not shown. It will be understood that a pull on the strap 4 in the direction of the small arrow will lift the pie tin support, and when the strap 4 is released, the weight of the support will 40 cause it to descend.

A form 7, which shapes the upper face of the pie crust 8 on the tin 1, is rigidly secured to the lower end of a stationary shaft or stud 9. Journalled on the shaft 9 above 45 the form 7, is a sleeve 10, which carries a bevel gear 11 at its upper end, and which also has rigidly connected therewith an arm 12. There is a depending stud 13 at the outer end of the arm 12, and journalled on 50 this stud is a rimming device in the form of a roller 14, which has a conically formed periphery for forming the rim of the pie crust, and which also has a groove 15 arranged to receive and confine the edge of

the pie tin 1 when the support 2 is at the 55 upper limit of its movement. This limit is determined by the engagement of the flange 16 of the support 2 with the bottom of the roller 14. In order to prevent a tendency of the shaft 3 to tilt when forced up against 60 the roller 14, a second roller 17 is provided. This need not be conical and should preferably be located clear of the edge of the pie tin, as shown. The roller 17 is carried by an arm 12^A and is geared similarly to the 65 roller 14.

The rimming roller 14 is caused to travel around the edge of the pie tin by rotating the arm 12, such rotation being accomplished by the pinion 18, which meshes with 70 the gear 11, and which may be driven by any suitable form of power mechanism connected with the shaft 19. In order to insure proper rotation of the roller 14, it has rigidly connected therewith a pinion 20, 75 which meshes with a stationary gear 21 mounted on the sleeve of the form 7.

The seat in the support 2, which receives the pie tin 1, is slightly larger than the corresponding part of the pie tin, so that the 80 pie tin may have a small amount of lateral movement in the seat, as may be seen from the space 22 in the drawing, and the bottom of the groove 15 in the roller 14 is of such diameter that when it engages the edge 85 of the tin, the tin will be crowded toward the opposite side of the form, as in the drawing, and its center will be slightly eccentric with respect to the axis of rotation of the arm 12. 90

As the roller 14 travels around the edge of the tin, the latter will be kept continuously shifting, and will have what might be said to be a gyratory movement with respect to the form, although neither the tin 95 nor the form rotates. This relative movement of the tin and the form causes the sides of the crust to be rolled to a thickness equal to the space between the form and the tin on the side adjacent to the rimming 100 roller 14, and will keep the form at all times free from the dough, and when the support 2 is lowered, the dough will descend with the tin without adhering to the form.

Although but one specific embodiment of 105 this invention is herein shown and described, it will be understood that numerous details of the construction shown may be altered or

omitted without departing from the spirit of this invention, as defined by the following claims.

I claim:—

- 5 1. In a pie crust rimming machine, the combination of means for supporting a pie tin, means for forming the inner face of a pie crust on such tin, rimming means for forming the outer edge of the crust, and 10 mechanism for rotating one of said means relative to another, said means being shaped and located so that said rotation will cause the tin and inner forming means to have a gyratory movement relative to each other.
- 15 2. In a pie crust rimming machine, the combination of a support for the tin, a form mounted above said support and adapted to engage the inner face of the crust on the tin, rimming means mounted to travel 20 around the form in a path concentric with the form and adapted to engage the edge of the tin and adapted to force it to a position eccentric with the form, whereby the tin will be given a gyratory shifting movement 25 with respect to the form, through the movement of said rimming means.
- 25 3. In a pie crust rimming machine, the combination of a support for the tin, a sta-

tionary form mounted above said support and adapted to engage the inner face of the crust on the tin, rimming means mounted to travel around the form in a path concentric with the form and adapted to engage the edge of the tin and adapted to force it to a position eccentric with the form, whereby 35 the tin will be given a gyratory shifting movement with respect to the form, through the movement of said rimming means.

4. In a device of the class described, the combination of means for supporting a pie 40 tin, inner crust forming means, and rimming means, one of said means being adapted when in engagement with the tin to hold it in a position eccentric to said inner crust forming means whereby the rotation of said 45 one means relative to said inner crust forming means will produce a gyratory movement of the tin with respect to said inner crust forming means.

Signed at Chicago this 9th day of September, 1910.

OLIVER COLBORNE.
